UNITED STATES PATENT OFFICE.

WILLIAM HERBERT McCANDLISH, OF LONDON, AND ALFRED BERNARD ROBSON, OF COUNTY OF HERTFORD, ENGLAND, ASSIGNEES TO SABULITE (GREAT BRITAIN) LIMITED, OF LONDON, ENGLAND.

COMPRESSOR FOR BUNDLED EXPLOSIVE MATERIAL.

1,297,375.

Specification of Letters Patent. Patented Mar. 18, 1919.

Application filed January 3, 1917. Serial No. 140,460.

To all whom it may concern:

Be it known that we, WILLIAM HERBERT McCANDLISH and ALFRED BERNARD ROBSON, subjects of the King of England, and residents, respectively, of London, England, and county of Hertford, England, have invented 5 certain new and useful Improvements in Compressors for Bundled Explosive Material, of which the following is a specification.

10 This invention relates to the compression of bundled material such as bundles of sticks of cordite or bundles of other material more particularly when they are of small dimensions.

15 Cordite sticks of uniform length can be made up into cylindrical bundles which can be encircled by bands, for instance, of silk tied around each bundle, each band being at 20 a point intermediate between the middle of the length of the bundle and its end. It is very necessary that these bands or "ties" should encircle the bundle tightly. The bundle has, therefore, as a preliminary to 25 the application of the ties, to be compressed to a diameter slightly smaller than that at which the ties are to retain it. While it is under this compression the ties are applied, and upon release of the compression, the 30 bundle expands slightly but not more than to an extent just sufficient to enable the ties, although they expand a little with the bundle, to keep it at the required final dimension.

35 The object of the present invention is the construction of a simple compressor into which the bundle can be readily inserted and which applies the required compression to the bundle at the middle of its length, while 40 leaving the ends exposed so that the operator can readily apply the ties to them.

45 According to the present invention the compressor comprises a tension member secured by one end, say by its upper end, to a fixed support on a work-bench and extending from this fixed support downward to and around a contractible circular clamp. This clamp is normally kept expanded by its own elasticity, or by a spring or other 50 means, and it virtually forms an intermediate round turn portion of the tension mem-

ber, the tension member extending onward and downward from the round turn to a treadle, lever or other device. When this device is operated, say by the foot of the operative, a pull is applied throughout the length of the member which will contract the round turn upon a bundle previously placed therein.

55 The detailed construction of the compressor may take various forms as illustrated in the accompanying drawings, in which—

Figure 1 is a perspective view showing a treadle-operated compressor;

Fig. 2 is a perspective view of an alternative construction of clamp;

Fig. 3 is a perspective view of an alternative form of clamp which is operated by a hand-lever, and

Fig. 4 is a perspective view of a bundle 70 of sticks tied together in the manner above described.

Like reference characters indicate like parts throughout the drawings.

75 Referring first to Fig. 1, it will be seen that the compressor is mounted on a suitably shaped bracket A which is clamped or otherwise secured to a table or bench B. The clamp within which the bundle of sticks is compressed, comprises a band of metal C 80 bent into a cylindrical form with the ends overlapping as shown at C¹; this band is secured at C² on to the front face of the bracket A near the upper end of it. The fastening C² is preferably situated nearer 85 one end of the band than the other in order to provide for the desired contraction and expansion of the cylindrical clamp. The free end C¹ of the band is secured to a tension member, conveniently by a perforated 90 tongue C³ receiving the end of a chain or the like D. This chain passes over a pulley D¹ mounted on a suitable spindle on the bracket A and extends downward through an opening B¹ in the bench B to near the 95 ground. There it is connected to a lever E constituting an operating-treadle. The lever E is pivoted at E¹ in any suitable manner and provided with a foot-plate E². A guide E³ may be provided to embrace the 100 lever E and guide it in its movements.

At the end C¹ of the band there is formed

on it, in any convenient manner, a radial projection C^4 , and a latch or detent F is pivotally mounted on the bracket A in such a position that it can engage and hold the projection C^4 .

The natural elasticity of the band C is utilized to maintain it in its expanded condition. In operating the device a bundle of cordite sticks or the like G , as illustrated in Fig. 4, is inserted into the band C when the latter is expanded; the treadle E E^2 is then pressed downward by the foot of the operative and the tension in the member D , being transmitted to the flexible band C , causes it to be contracted, and compress the bundle G at about the middle of its length. The projection C^4 is so positioned on the end C^1 of the band C that when the desired amount of compression has been given to the bundle, the latch F engages the projection C^4 and holds the band C in its contracted position. The operative is thus relieved of the necessity of maintaining pressure on the treadle E E^2 during the rest of the operation. When the bundle is compressed, threads of silk or the like G^1 are tied around the bundle G intermediate of the middle of its length and its ends, as shown in Fig. 4. When these have been tied, the operative lifts the latch F to release the band C which then expands by virtue of its own resiliency and the bundle G is readily removed and a new bundle inserted in its place. This cycle of operations is then repeated.

In the modification illustrated in Fig. 2, the clamp is constituted by two parallel turns of wires. The wires H H^1 are secured by their ends near the top of the bracket A and extend downward therefrom, and then outward into a circle and back to lie against the face of the bracket A . One or more spacing pieces H^2 may be secured to the wires to maintain them at the correct distance apart. The lower ends of the wires H H^1 are secured to a cross-head J which conveniently slides on a dove-tail or other guide J^1 integral with, or secured to, the bracket A ; the lower ends of the wires H H^1 are thereby maintained in their correct position. The cross-head J is connected by a tension member D to a suitable treadle, lever or the like for moving it downward.

Since the wires H H^1 may not be sufficiently resilient in themselves to expand the clamp, after it has been contracted, a spring K is attached to the cross-head J and to the bracket A , and is so arranged that it is strained when the cross-head J is moved downward to contract the clamping wires. The expansion of the clamping wires, when released, is then effected by the spring K causing the cross-head J to move upward to its original position. The operation of this device is similar to that described with reference to Fig. 1.

In the modification illustrated in Fig. 3, the clamp takes the form of a band of resilient metal L secured at one end to the bracket A and bent into a round turn perpendicular to the face of the band. The band is slotted centrally at L^1 where it commences its curvature, and is correspondingly reduced in width at L^2 where it has completed its round turn. The reduced part L^2 passes through the slot L^1 and extends downward, if desired, through suitable guides, and constitutes a tension member L^3 . This figure illustrates an alternative method of operating the clamp for contracting it, a hand-lever being provided for this purpose instead of a treadle as already described. Obviously, however, either the treadle or the lever may be used with any of the forms of clamp above described. The hand-lever M is rotatably mounted on a spindle M^1 and coupled to a disk or crank M^2 coupled to a connecting-rod M^3 which is in turn connected to the tension member L^3 of the clamp. A bracket M^4 may be provided to guide the hand-lever M and constitute a stop for it, the stop being so disposed that the lever M is held from further movement when the crank has just passed its lower dead center. Obviously, instead of a disk and crank-pin, or a crank, an eccentric disk and straps could equally well be used. In this construction there is no need to provide a detent corresponding to the latch F to hold the clamp in its contracted position, since the movement of the crank-pin past its dead center provides an automatic lock.

From the foregoing it will be seen that the clamp, and its ends, and the actuating device therefor, are symmetrically situated with relation to a central plane transverse to the axis of the bore of the clamp.

What we claim as our invention and desire to secure by Letters Patent is:—

1. In apparatus for compressing bundled material, the combination of a supporting frame, a contractile circular clamp secured thereto, and a tensioning member operatively connected to said clamp to contract the same when tension is applied to said member, said clamp having spring means whereby it will automatically expand when the tension is removed, substantially as described.

2. In apparatus for compressing bundled material the combination of a supporting frame, a contractile circular clamp secured thereto, a tension member operatively engaging said clamp so as to contract it when tension is applied to said member, means for expanding said clamp when the tension is released, and means for applying tension to said member.

3. In apparatus for compressing bundled material the combination of a supporting frame, a band of metal secured near one

end to said frame and extending in a circular formation therefrom so that the other end overlaps the first end, a tension member forming an extension of the said overlapping end, a guide on said supporting frame for said tension member, a lever for applying tension to said tension member, a lug

on said overlapping end and a detent pivoted on said supporting frame to engage said lug when the clamp is in its contracted form. 10

In testimony whereof we have signed our names to this specification.

WILLIAM HERBERT McCANDLISH.

ALFRED BERNARD ROBSON.
